WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

HEAD FOR LOOM WARP BEAMS.

Application filed June 21, 1927. Serial No. 200,479.

This invention relates to loom beams on which the warp supply is wound and it is the principal object of the invention to provide an improved head for the beam which will prevent the total loss of the head should the 5 yarn retaining flanges become broken.

The heads for warp beams such as ordinarily used in looms are usually formed with integral parts, namely, a flange which defines 10 the warp space and a device to resist movement of the beam in the letting-off of the warp threads. In looms for weaving such fabrics as cotton, gingham or worsted the position for resisting movement of the beam 15 has been a smooth drum around which extends a leather strap, coiled rope or other flexible device which exerts friction on the drum to serve as a let-off. It has been customary to form the friction drum and the 20 flange all in one piece and I find that when the flange breaks due to falling or improper handling it has been necessary heretofore to throw away the whole head. The drum in such cases might be in perfect condition but 25 it must nevertheless be wasted because of the fact that it is cast integral with the flange. Moreover the drum is subject to more or less machining during the manufacture of the head and these machining operations and 30 their cost must be lost when any part of the flange becomes defective. It is an important object of my present invention to make a beam head wherein the flange and friction drum shall be separate but held together in 35 such a way that they will rotate together so that resistance offered to the movement of the drum by the friction devices will be communicated to the warp through the flange and the beam barrel connected thereto.

40 While the flange and friction drum should lie as close together as possible yet it may be desirable under certain conditions to be able to move the friction drum longitudinally of the beam with respect to the flange, such for 45 instance as to accommodate slightly varying distances between the supporting bearings of the beam on the loom sides, and this result I achieve by the herein described construction whereby the drum and flange parts are relatively movable.

With these and other objects in view which will appear as the description proceeds, my invention resides in the combination and arrangement of parts hereinafter described and 55 set forth in the claims.

In the accompanying drawings, wherein I have shown a convenient embodiment of my invention,

Fig. 1 is a rear elevation of the beam made according to my present invention, certain 60 parts of the loom supporting structure and let-off devices being shown in section,

Fig. 2 is an end elevation of one of the beam heads looking in the direction of arrow 2, Fig. 1,

Fig. 3 is a vertical section on line 3-3 of Fig. 2, and,

Fig. 4 is an enlarged horizontal section taken on line 4-4 of Fig. 2.

Referring to the drawings I have indicated 70 the loom stand 10 as having supporting bearings 11 on which the beam is mounted. The beam is provided with a barrel 12 on which the warp thread is wound, said barrel being provided with two or more slots 13 which 75 receive tie rods 14 extending the length of the barrel 12.

Each end of the beam is provided with a head which in the present instance is formed of two parts, the flange section 20 having a 80 hub 21 and an inside face 22, the inside faces of the flanges defining the space to be occupied by the warp threads. As shown herein each flange section 20 is provided with one or more tongues 23 for a purpose to be described and the rods 14 extend through the flange sections and carry nuts 24 which bear 85 against the outer faces of the flange sections to hold the latter against the core or barrel 12. Each flange section is provided with a 90 supporting gudgeon 25 which passes through the section and into the adjacent end of the barrel 12. The gudgeons may be secured to the barrel in any approved manner and rest in the loom bearings 11. Each flange is provided 95 with a relatively thin circular rim 26 which extends outwardly beyond the tongues 23.

The drum portion 30 of each head is provided with a hub 31 which is secured to the 100 corresponding gudgeon 25 by a set screw 32 and each drum portion is provided with a friction face 33 and a rib 34 which serves to confine friction elements as indicated at 105 in Fig. 1. Each drum section is provided with one of more sockets 36 for each of the tongues 23, said tongues fitting the sockets snugly and being held in proper longitudinal position by nut 32 in the hub 31.

It will be obvious that assemblage of the 110

two-part head and the barrel is accomplished by fitting the end of the barrel in a shouldered recess 37 in the head, and passing the tie-rods 14 through the shoulder, as illustrated in Fig. 3.

When assembled as set forth herein the tongues 23 and sockets 36 will cooperate to require the flange portion 20 and the corresponding drum portion 30 to rotate in unison about the axis of the gudgeons and the rib 34 on the drum portion will cooperate with the rim 26 to define a space for the reception of the friction rope, cord, drum or other flexible let-off element indicated at 35. So long as the parts remain intact the beam will operate in the usual manner but should one of the flanges become broken the corresponding drum can be removed and the damaged flange replaced, after which the same drum portion can be put in place and the beam restored to usefulness. In this way the cost of making repairs is considerably lessened. I have described the replacement as being due to the breaking of the flange portion 20 as this has been found the part to require replacement in actual practice, but the invention of course is also useful should the drum be broken while the flange portion is uninjured.

From the foregoing it will be seen that I have provided a two part head for a warp beam including yarn restraining flange portions secured to the beam barrel and a separate drum portion to cooperate with the let-off of the loom, these portions being interlocked so that movement of the flange under the influence of the feeding of the warp is communicated to the drum and resisted by the friction element 35.

Having thus described my invention it will be apparent that changes and modifications may be made therein by those skilled in the art without departing from the spirit and scope of the invention and I do not wish to be limited to the details herein disclosed, but what I claim is:

1. In a warp beam for looms, a cylindrical barrel for the warp, a flange member secured to the barrel and having a tongue, a friction drum formed independently of the flange member but held in fixed longitudinal position with respect to the barrel and having a socket, said socket to receive the tongue to form interlocking means connecting the flange and drum members to act independently of the barrel to prevent relative angular movement of said flange and drum members and cause the drum member to rotate with the barrel.

2. In a warp beam for looms, a cylindrical barrel for the warp, a flange member held in fixed angular relation with respect to the barrel, a friction drum member formed separately from the flange member and held against longitudinal movement with respect to the barrel, and a projection formed on one

of said members to enter a recess in the other member to act independently of the barrel to prevent relative angular movement of the members whereby angular movement of the barrel is communicated to the drum member. 70

3. In a warp beam for looms, a cylindrical barrel for the warp, a flange member secured to the barrel and held against relative angular movement with respect to the barrel, a drum member formed separately from the 75 flange member, and detachable inter-engaging means formed on the members and acting independently of the barrel to prevent relative angular movement thereof and to cause the drum member to move angularly with the 80 barrel.

4. In a warp beam for looms, a cylindrical barrel for the warp, a flange member held in fixed angular position with respect to the barrel, a gudgeon extending from the barrel through the flange member, a drum member secured to the gudgeon and formed independently of the flange member, and inter-engaging means formed on the flange and drum members and acting independently of the 90 barrel to prevent relative angular movement thereof and cause the barrel and the drum member to move together angularly. 85

5. In a warp beam for looms, a cylindrical barrel for the warp, a flange member held in fixed angular relation with respect to the barrel, a supporting gudgeon extending from the barrel through the flange member, a drum member formed independently of the flange member and movable longitudinally along the gudgeon but normally held to said gudgeon in fixed longitudinal position with respect to the barrel, and inter-engaging means formed on the flange and drum members and acting independently of the barrel to prevent 100 relative angular movement of said members and to cause said drum member to move angularly with the barrel. 105

6. In a warp beam for a loom operating with a device effective to resist rotary movement of the beam, a substantially cylindrical barrel forming the body of the beam, a flange secured to the barrel and having a portion extending substantially perpendicular to the barrel to define one side of the warp space, and a friction drum having a portion substantially concentric with the axis of the barrel, said portion having a rim opposite the aforesaid flange on one side and on the other side abutting said flange to form therewith a 115 space to receive the device. 120

7. In a warp beam for a loom operating with a device effective to resist rotary movement of the beam, a substantially cylindrical barrel forming the body of the beam, a flange secured to the barrel and having a warp spaced limiting portion substantially perpendicular to the barrel, a friction drum formed separate from the flange and having a cylindrical surface terminating at one side 130

in the rim and having the other side in abutment with the aforesaid flange, said flange together with the cylindrical portion of the friction member and the rim of the latter defining a space for the friction device.

8. In a warp beam for a loom operating with a device effective to resist rotary movement of the beam, a substantially cylindrical barrel forming the body of the beam, a warp limiting flange secured to the end of the barrel and having a portion extending substantially perpendicular to said barrel, a friction member formed separate from said flange and

having a cylindrical portion at one end of which is formed a rim and the other end of which lies in substantial contact before said perpendicular portion of the flange to define with the latter a space for the device and interengaging means between the flange and drum to cause said flange and drum to move in unison and in substantially fixed angular position relatively to the warp beam.

In testimony whereof I have hereunto affixed my signature.

WILLIAM M. WATTIE.
